Des. 186,084
Patented Sept. 8, 1959

186,084

WHEEL UNBALANCE DETECTING UNIT

Arthur F. Dean, Glenview, and Anton J. Panzica, Hinsdale, Ill., assignors to Stewart-Warner Corporation, Chicago, Ill., a corporation of Virginia

Application January 27, 1958, Serial No. 49,421

Term of patent 14 years

(Cl. D52—1)

FIG. 2.

Fig. 1 is a perspective view taken from the front and to one side of a wheel unbalance detecting unit, embodying our new design; and

Fig. 2 is a perspective view taken from a point diametrically opposite that of Fig. 1.

We claim:

The ornamental design for a wheel unbalance detecting unit, substantially as shown.
